UNITED STATES PATENT OFFICE.

MARK ARONSON, OF NEW YORK, N. Y.

DESIGN FOR A SASH-BELT.

SPECIFICATION forming part of Design No. 27,161, dated June 1, 1897.

Application filed March 17, 1897. Serial No. 628,053. Term of patent 3½ years.

To all whom it may concern:

Be it known that I, MARK ARONSON, of the city, county, and State of New York, have invented and produced a new and original Design for a Sash-Belt for Ladies, of which the following is a full, clear, and exact description.

5 The figure is a front elevation of a sash-belt for ladies, showing my design.

10 The leading feature of my design consists of the panels A A interposed transversely of

the longitudinally-extending plaits B of the body of the belt.

A minor feature consists of the bow ornamentation C on one end of the belt. 15

I claim—

The design for a sash-belt for ladies as herein shown and described.

MARK ARONSON.
